UNITED STATES PATENT OFFICE.

PHILIP M. EARLE, OF JACKSONVILLE, FLORIDA.

DESIGN FOR A DUPLEX EGG-TESTER.

SPECIFICATION forming part of Design No. 26,329, dated November 24, 1896.

Application filed September 24, 1896. Serial No. 606,899. Term of patent 14 years.

To all whom it may concern:

Be it known that I, PHILIP M. EARLE, a citizen of the United States, residing at Jacksonville, in the county of Duval and State of Florida, have invented and produced a certain new and original Design for a Duplex Egg-Tester; and I do declare the following to be a full, clear, and exact description of the invention, such as will enable others skilled in the art to which it appertains to make and use the same.

My invention relates to a design for a duplex egg-tester which can be attached to any ordinary lamp. It relates to the entire configuration of the tester and to a tester constructed of sheet metal or any other suitable material.

My invention relates particularly to a tester as illustrated in the accompanying drawing, in which the figure represents a perspective view of a duplex egg-tester embodying my design.

The leading features of my design appear in the following description.

A represents a rectangular body or shield having flanged upright sides, as shown, provided with oval openings *a a*, centrally located within the diverging side flanges.

B B are converging wire arms, their outer ends being joined by a C-shaped flat clamp.

The upper wire arms D D are formed with a crescent-shaped yoke E.

Having thus described my design, what I claim as new, and desire to secure by Letters Patent, is—

The design for a duplex egg-tester, substantially as herein shown and described.

In testimony whereof I hereunto affix my signature in presence of two witnesses.

PHILIP M. EARLE.
